LIVE CENTER

Van F. Lippard, Washington, D. C.

Application March 13, 1937, Serial No. 130,773

12 Claims. (Cl. 82—33)

The present invention relates to a live center for tail stocks in metal working machines.

The invention is applicable to any type of machine in which a piece of work is supported between centers, and is rotated by driving means, during which rotation a metal working operation is performed upon the piece of work.

The invention comprises essentially a live center assembly, in which the center that supports the work is adjustable transversely of the assembly in order to support the work eccentrically upon its axis of rotation.

One object of the invention is to provide a live center assembly having means whereby the center may be adjusted to rotate eccentrically of the assembly.

Another object is to provide micrometer adjustment means, whereby the degree of eccentricity may be controlled.

Still another object is to provide means for insuring the turning of the center with the work in order to cause the rotary motion of the work to be eccentric.

Still another object is to provide supporting means for the end of the work engaged by the center in a yielding manner to permit eccentric rotation.

The field to which the invention is particularly directed, and in connection with which it was developed, is that of grinding pistons.

In modern internal combustion engines, and especially automobile engines, it is customary to use pistons that are not truly cylindrical. The pistons that are used are what are termed in the industry as cam-ground pistons, which means that they are slightly oval in form, particularly adjacent their tops, this being to allow for unequal expansion due to the pin-supporting structure carried within the pistons.

In manufacturing pistons it is customary to form the pistons in the form of a true cylinder, and then by a grinding operation, bring the pistons to the requisite slightly oval form. Heretofore this grinding operation has been performed by highly complicated and expensive grinding machines. By means of the present invention this grinding operation may be performed by any ordinary grinding machine. In addition to the above described use, the invention is applicable to turning, or any other field of metal working where it is desired to form an eccentric object.

In the accompanying drawing:

Figure 1 is an elevation showing schematically a piston supported between an adapter and

a live center constructed in accordance with the present invention.

Figure 2 is a plan view, the piston being shown in section.

Figure 3 is an elevation of the front face of the center assembly.

Figure 4 is a sectional view on the line 4—4 of Figure 2.

Figure 5 is a sectional view of the center assembly.

Figure 6 is a sectional view on the line 6—6 of Figure 5.

Describing the drawing more particularly, and referring first to Figures 5 and 6, the live center assembly includes a supporting element 1 having the form of a standard taper, but which may be of any desired configuration to fit the tail stock of a machine. At its forward end the supporting member 1 may carry a flange 8 extending annularly, and forming the rear wall 20 of a bearing enclosure 9. Extending forwardly centrally of the flange 8 is a stud 10 that supports one element 11 of a ball race 12, the element 11 being advantageously mounted on the stud 10 by a press fit.

Revolvably carried by the stud 10 and bearing member 11 is a head 13 comprising an annular cup-like member 14 having a front wall 15 and circular side wall 16. The side wall 16 carries internally a ball race member 17 advantageously press fitted therein and cooperating with the member 11 and balls 18 to revolvably support the head 13 upon the stud 10. The side wall 16 has edges formed to cooperate with the edges of the wall 8 to form a grease seal to exclude dirt and to maintain a supply of lubricant within the enclosure 9. A grease port 19 may be provided.

It will be seen from the structure so far disclosed that the head 13 is concentrically revolvably upon the stud 10. In order to provide for adjustable eccentric rotation, the following center structure is provided.

The front wall 15 of the head 13 is provided with a transverse dovetailed mortise 20, the said mortise passing through the center of rotation of the head. Advantageously the mortise may be formed in a projecting rib-like extension 21 formed integrally with the wall 15, and having at each side a shoulder 22.

Slidably mounted within the mortise 20 and shaped to closely engage the sides of the mortise is a carriage member 23 preferably substantially equal in length to the diameter of the front wall 15. The member 23 carries at its central portion

10

45

50

55

a cone-shaped center 24 that projects forwardly of the front face 25 of the rib 21, and that is designed to engage and support the center of the piston or other work to be operated upon. An adjusting screw 26 controls the position of the carriage 23 and therefore of the center 24. The screw 26 is threaded into a bore 27 in the wall 15 of the head, the bore being positioned closely adjacent the inner surface of the mortise 20. Preferably the threads of the bore 27 and of the screw 26 are of a micrometer type, so that longitudinal movement of the screw will bear a definite relation to its amount of rotation. The screw 26 has an enlarged head 27a that overlies and engages the end of the carriage 23. It will be apparent that upon rotation of the screw in a direction to cause the head to travel toward the center of the assembly the enlarged head 27a bearing upon the end of the carriage 23, will cause the carriage to move in a direction of motion of the screw. Preferably the screw is provided with a pointer, as at 28 in Figure 2, and the wall of the head is provided with a scale 29, so that a determined adjustment may be easily made. Upon the opposite side of the head is mounted a backing screw 30 threaded into the wall 15, and having an enlarged head 31 that contacts the opposite end of the carriage 23. By means of this screw, the carriage may be secured in adjusted position and by tightening the screw, the carriage will be tightened against the head 27a of the screw 26, insuring that the scale reading is accurate. A scale 29a may also be provided in the front face of the assembly.

From the foregoing description, it will be apparent that rotation of the head 13 upon the stud 10 will cause the center 24 to revolve in a planetary manner around the center of rotation of the assembly, assuming that the carriage has been moved to place the center in a position removed from the center of rotation of the assembly. It will also be apparent that the circular rotation of the center will cause a piece of work held between the center and a driving center of a machine, to rotate in an eccentric manner.

In order to insure that the desired eccentric rotation will occur, instead of concentric rotation between centers that are not in line, it is necessary to insure that the head 13 rotates upon the stud 10. Means are provided for insuring rotation of the head 13 by the rotating work. This means is provided in the form of spring fingers 32 mounted upon the front face of the wall 15 at either side of the rib member 21, and abutting the shoulders 22 thereof. The spring fingers include end portions 33 that lie closely adjacent the surface, and which are held by screws 34 having heads that overlie these end portions. The fingers proper are bent outwardly and extend angularly forwardly from the portions 33 and in a direction opposite to that in which the head rotates, and terminate in sharp cornered edges 35. The sharp corners of the edges 35 engage the surface of the work, as shown in Figures 1 and 2, with sufficient security to insure that the head 13 rotates upon the stud 10. Inasmuch as the rotation of the work is eccentric, the distance between the face of the work, as the top surface 36 of the piston 37, shown in Figures 1 and 2, and the front surface of the head, constantly varies. The resilient nature of the spring fingers 32 permits this variation.

In Figures 1 and 2 is illustrated, somewhat schematically, the method of use of the center assembly. A piston 37 is shown mounted between

the center 24 and the head stock 38 of a grinding machine, the head stock being provided with an adapter 39 equipped with a driver 40 in accordance with standard practice. The driver 40 extends forwardly from the adapter and engages one of the pin bosses 41 of the piston to rotate the piston.

Assuming that it is desired to eccentrically grind the top portion of the piston, as shown in Figure 2, the screw 26 is turned to give the proper degree of eccentricity of rotation to the piston, as indicated by the scale 29. With the grinding instrumentality of the grinder set at the proper distance, the machine is started, and as the piston rotates eccentrically, the grinder will operate upon a portion of its surface at each revolution. When the grinding operation has been completed upon one side of the piston, the piston is reversed in its position with relation to the center so that the opposite side may be ground. The reversing operation may be accomplished by holding the head 13 against rotation, and by hand turning the head stock 38 in a direction reverse to its normal direction of rotation, or it may be accomplished by holding the piston and turning the head 13 in a forward direction. In either method the sharp edges of the fingers will slide easily over the top surface of the piston. The reverse motion may be imparted to the head stock from any suitable part of the machine that is accessible to the hand of the operator.

In order that the grinding may take place at the proper point on the surface of the piston, the center of the head of the screw 26 is lined up with the center of the pin hole 42 of the piston, and upon reversal of the piston, as above described, the opposite pin hole is lined up with the screw 26. The head of the screw 26 indicates the portion, that during the rotation of the piston, is farthest from the center of rotation of the head. Where it is desired to grind off a portion of a piston other than that adjacent the pin hole, the portion to be operated upon may be easily selected by lining it up with the screw 26.

Referring further to Figures 1 and 2 it is sometimes necessary that a piston be cam-ground only in its uppermost portion, while sometimes it is necessary to cam-grind the piston throughout its length. Where only the upper portion is intended to be ground, the procedure as above described is correct. Where, however, it is necessary to cam-grind a piston throughout its length it becomes necessary to rotate the complete piston, as distinguished from one end of the piston, eccentrically. In Figure 1 the method of doing this is illustrated. A piece of shim stock or other material of proper thickness, as illustrated at 42 in Figure 1 is inserted between the surface of the adapter 39 and the inner surface of the piston. Where it is desired to grind off the same amount of the piston throughout its length and along one side, the material 42 will be selected of the same width as the amount that the center 24 is moved off center. It will be readily realized that different degrees of taper in the ground area may be provided by relating the thickness of the material 42 to the adjustment off-center of the center 24.

By use of this center assembly, any sort of eccentric operation may be performed in a machine in which the work is supported between centers. While it has been described as applied to a machine for grinding pistons, it will be readily apparent that it may be applied to other metal working machines in which the work is revolved.

The assembly provides for controlling the eccentricity given to the rotation of the work with the utmost precision. The assembly is simple and relatively inexpensive to construct, and by 5 its use, an ordinary rotary metal working machine may be used for operations that heretofore required the use of complicated and highly specialized machines.

It is an essential feature of the invention that 10 the adjustment of the center with respect to the center of rotation be located forwardly of the bearing assembly that permits turning of the head with respect to the stationary portion of the assembly, because an adjustment located 15 rearwardly of the bearing assembly would result merely in two out-of-line centers, by means of which a tapered piece of work could be produced, but which would not cause eccentric rotation of the work. Similarly a dead center adjustable to 20 a position out of line with the driving center will result in a tapered piece of work, rather than an eccentric one because the work rotates upon a dead center and does not result in eccentric rotation of the work.

From the foregoing it is thought that the construction, operation and many advantages of the herein described invention will be apparent to those skilled in the art without further description, and it will be understood that various 25 changes in the size, shape, proportion and minor details of construction may be resorted to without departing from the spirit or sacrificing any of the advantages of the invention.

What I claim, is:

- 35 1. In a live center assembly for machines, a stationary stud for mounting in the tail stock of a machine, a head rotatably mounted on the stud, and a center movably mounted on the front face of the head for adjustment transversely of the head.
- 40 2. In a live center assembly for machines, the said assembly including a stationary stud and a head rotatably mounted on the stud, a center mounted on the front face of the head for movement transversely of the head, and work-engaging means carried by the head for engaging work supported by the center for driving the head from the work.
- 45 3. In a live center assembly for machines, the said assembly including a stationary stud and a head rotatably mounted thereon, and having a front face, the combination with a center mounted on the front face of the head and adjustable transversely of the face, of spring means carried by the face and located out of the line of adjustment of the center, the said spring means extending from the face of the head to a point where they are engageable with work engaged with the center.
- 50 4. In a live center assembly for machines, the said assembly including a stationary stud and a head rotatably mounted thereon and having a front face, the combination with a center mounted on the front face of the head and adjustable transversely of the face, of spring fingers secured to the face at either side of the center, and extending angularly outward from the face of the head and in a direction opposite to the direction of rotation of the machine.
- 55 5. A live center assembly for machines comprising a stationary stud, a head rotatably mounted on the stud and having a dovetailed

mortise extending transversely across its front end and passing through the center of rotation, a carriage member slidably engaged in the mortise, means for securing the carriage against movement in the mortise, a forwardly extending center mounted upon the carriage, and spring fingers mounted at either side of the mortise, the said fingers each extending angularly forward of the face in a direction opposite the direction of motion of the machine and forwardly of the front face of the head to a point to be engaged by work in the machine.

6. In a grinding machine, the combination with a driving center and a tail stock substantially in line with the driving center, of a live 15 center having a stationary stud engaged in the tail stock and substantially in line with the driving center, a head rotatably mounted on the stud, and a center movably mounted on the rotatable head and for transverse adjustment thereon. 20

7. In a machine for eccentrically grinding pistons, a revolute support for one end of a piston, a second revolute support for the other end of the piston, and means carried by the second revolute support for holding the end of the piston 25 in eccentric relation to the axis of rotation of the said second revolute support.

8. In a machine for eccentrically grinding pistons, including a head stock and a tail stock, the combination with a driving support for one end 30 of a piston, of a live tail-center comprising a stationary stud mounted in the tail stock, a head rotatably mounted on the stud and transversely adjustable means carried by the revolute head for supporting the other end of the piston. 35

9. In a live center comprising a stud for stationary mounting in a machine, a head revolvably mounted upon the stud and having a front surface, and a center movably mounted on the front face of the head, and at one side of the center 40 line of the stud for eccentric rotation about the axis of the stud.

10. In a live center comprising a stud for stationary mounting in a machine, a head revolvably mounted upon the stud, and having a mortise 45 extending transversely of its front face, a center slidably mounted in the mortise, and screw threaded means carried by the revolute head for adjusting the position of the center in the mortise, the said screw threaded means being accessible at the side of the head for operation while the center is mounted in a machine. 50

11. The process of eccentrically grinding pistons that comprises supporting a piston between centers, rotating one center and the end of the piston supported thereby eccentrically, and during said rotation grinding off a portion of the piston along a line parallel to the center of rotation of the piston. 55

12. The process of eccentrically grinding pistons that comprises rotating a piston eccentrically between centers, during such rotation grinding off a portion of one side of the piston along a line parallel to its center of rotation, reversing the eccentricity of rotation of the piston between the centers by rotating the piston with respect to the centers, and grinding off a second portion of the piston on the opposite side to that first ground along a line parallel to the center of rotation of the piston and during its rotation. 60
